IONIZING STRUCTURE

Elmer G. Hills, Chicago, Ill., assignor, by mesne assignments, to Westinghouse Electric Corporation, East Pittsburgh, Pa., a corporation of Pennsylvania

Application March 1, 1947, Serial No. 731,734

5 Claims. (Cl. 183—7)

1

This invention relates to the production of ionization and more particularly to an improved apparatus for producing ions for the process of electrostatic precipitation of particles of solids or liquids from gases, as in the cleaning of air for air conditioning.

In electrostatic precipitators which are used for air conditioning, the air to be cleaned is first drawn or blown through an ionizing zone or chamber, where the foreign particles to be removed are first ionized or charged, and then through a precipitating zone or chamber where the charged particles of dust are made to precipitate or collect on a plurality of spaced, parallel, collector plates parallel to the general direction of gas flow, adjacent ones of which are at different potentials with respect to each other, so that the charged particles will be deflected toward a plate and precipitated thereon.

For efficient and commercially acceptable operation of this type of precipitator, the ionizing field must be sufficiently intense to charge substantially all of the particles of dust flowing through it, but the ionizing currents preferably are such that negligible ozone generation occurs. In ionizing means generally used at present, fine wires are placed alternately between plane or curved electrodes having large radii of curvature, and the wires are placed at either a positive or negative potential of such magnitude with respect to the large curved electrodes that the gas to be cleaned is ionized as it passes between the electrodes. In order to obtain sufficient ionization with ionizing structures of this type, it is necessary to use very high voltages or very fine ionizing wires or both. In many ionizers, both voltages as high as 15,000 volts, and wires as fine as 5 mils in diameter are used in order to obtain the required results. These wires must be supported by high voltage insulators and often are suspended in lengths of several feet with no other supports than at their ends. This makes for mechanical structures that are extremely fragile and easily broken. Because of the necessary placement of the ionizing chamber on the intake side of the gas cleaner, large quantities of lint, dust, and other particles may have to pass through the ionizing chamber often causing electrical arcs to occur between the fine wires and their cooperating electrodes, which arcs may melt the fine wires thus putting the apparatus out of operation. In view of the fact that the ionizing wires collect large amounts of grease, dust and other matter, it is very difficult to clean them because of danger of breaking or stretching

2

them so that they cause large nonuniformities of the electrical field in the ionizing chamber and even electrical arcs or flash-overs. These disadvantages cannot be eliminated by merely supporting the wires at more points or all along their lengths with insulating means because of the fact that any dielectric placed near an ionizing wire causes a reduction in ionization. Actual measurements which I have made show that the amount of ionization produced by a wire 11 mils in diameter excited at 20,000 volts D. C. with respect to its cooperating electrodes drops to less than ten percent of its former value when a $\frac{1}{16}$ " diameter glass rod is brought near it.

The reason for this is that if the wire were, say, positive, positive ions would be repelled from it and collect on the surface of the glass rod placed near it. The effect of these ions collecting on the glass rod is to cause the rod to reach a potential substantially the same as that of the ionizing wire with the result that the electrostatic lines of force formerly coming from the relatively large negative electrodes of the ionizing structure and terminating on the ionizing wire now terminate on the glass rod instead, thus reducing the field gradient in the immediate vicinity of the wire to such an extent that the ionization produced by the wire decreases tremendously. I have further found that by superimposing an alternating component of voltage of several hundred kilocycles on the voltage applied to the ionizing wire that the amount of ionization produced by the wire actually increases rather than decreases when a dielectric material is brought near the wire. This increase in ionization due to the presence of the dielectric not only makes possible the operation of the ionizing wire at a lower potential, but makes possible the fastening of the wire to a dielectric member along its entire length thus giving great rigidity to the ionizing structure. The use of a dielectric backing for the ionizing conductor makes possible the economical construction of ionizing electrodes of other shapes than fine wires such as electrodes having many points which electrodes can be metal sprayed, plated, sputtered, evaporated, or otherwise placed on a dielectric such as glass in the form of a thin film.

It is therefore an object of my invention to provide an ionizing means which is mechanically rugged, and can be cleaned without any substantial danger of breaking, bending, stretching, or otherwise misaligning it. It is a further object of my invention to provide an ionizing means that requires a smaller magnitude of voltage for its

excitation with the resulting economies and freedom of danger from shocks, fires, and arc-overs. It is still a further object of my invention to provide an ionizing means that can be manufactured economically with the amount of spoilage in production, handling and shipping reduced to a minimum. It is still a further object of my invention to provide an ionizing means that can be cleaned easily.

With the foregoing and other objects in view, my invention consists of the features, elements, combination and apparatus hereinafter described and claimed, and illustrated in the accompanying drawing, in which:

Figure 1 is an end view of an ionizing structure showing the lines of force existing between the electrodes.

Figure 2 is an enlarged end view of the ionizing wire and dielectric rod forming part of the ionizing structure of Figure 1.

Figure 3 is an end view together with a fragment of a top view of an ionizing electrode which is representative of a second embodiment of my invention.

Figure 4 is an end view of an ionizing electrode which is a variation of the electrode of Figure 3.

Figure 5 is an end view and a fragment of a top view of another embodiment of my invention.

Figure 6 is a circuit diagram illustrating one manner in which the dielectric-backed electrodes of my invention could be excited from a source of alternating current energy.

Referring to Figure 1 of the drawing electrodes 12 represent a plurality of electrodes of relatively large radii of curvature between which electrodes and ionizing wire 11 the exciting voltage of the ionizing structure is applied. Member 13 is a rod made of some dielectric material such as glass which is maintained in contact with wire 11 by suitable means substantially throughout the length of the wire. Because of the presence of the dielectric 13, the electrical capacitance of the discharge path between the wire and electrodes 12 through the dielectric 13 is increased, since the dielectric constant of the member 13 is greater than that of air, or the gas to be cleaned. This increased electrical capacitance means that there is a greater number of electrostatic lines of force linking electrodes 12 with electrode 11 for the same voltage difference between the electrodes 12 and electrode 11. This increased number of lines of force terminating on electrode 11 means that there is an increased field gradient in the immediate vicinity of electrode 11 with a resulting increase in ionization. As the dielectric 13 is not positioned directly in the path between the electrodes 11 and 12, and there is a free path between the electrodes through the gas medium unobstructed by the dielectric, the overall capacity between the electrodes is not substantially more than that provided by the gas medium.

The amount of ionization produced is increased still further by another phenomenon. Figure 2 shows an enlarged view of dielectric rod 13 and wire 11. Due to the fact that both the rod and the wire have the form of circular cylinders in this embodiment of my invention they touch each other only along a single line parallel to the axes of the two cylinders. The largest number of electrostatic lines of force that terminate on the conductor 11 reach it by passing upward through the dielectric rod due to the fact that the rod has a greater electrical permittivity than does the gas surrounding it. These lines of

force passing through the dielectric rod terminate on the under side of the wire in the regions 14, as shown in Figure 2. Since the lines tend to concentrate in the relatively small regions 14 rather than to distribute themselves evenly around the wire the electrostatic stress concentration is even greater in regions 14 due to the presence of the dielectric rod 13 thus giving increased ionization for the same voltage. This greater stress concentration can be seen experimentally by observing the corona discharge from such a wire backed by a dielectric and excited with a source containing a high frequency component of alternating voltage. The side of the wire farthest from the dielectric appears dark as if there were no discharge from it at all but the side of the wire nearest the dielectric glows very brightly with streamers that spread downward toward the dielectric rod on each side of the wire.

As explained earlier the desirable effects of the addition of the dielectric rod could not be realized if the ionizing electrode were excited with direct current alone. This is because ions produced in the gas between the regions 14 on the wire and regions 15 on the dielectric rod tend, as all ions in gases do, to move parallel to the lines of force in the electrical field and reduce the charges on the electrodes that have set up the field. This means that if electrode 11 were charged positively that positive ions would move away from it along lines of force and would deposit themselves on regions 15 of the dielectric rod 13. As soon as enough ions had deposited themselves on rod 13 its potential in the regions 15 would become substantially equal to that on the wire 11 and the field existing between regions 14 of the wire and 15 of the rod would be reduced to such a value that ion production would be reduced to an extremely low value or cease entirely. This charging phenomenon may be likened to the phenomenon occurring in an electrical circuit in which the ionized and therefore conductive path through the gas between regions 14 and 15 may be compared to an electrical resistance which is connected in series with a condenser (which condenser has as its dielectric the series combination of the dielectric of rod 13 and the gas through which the lines of force flow in linking electrodes 11 and 12, and which condenser has as its electrodes the charged region 15 and the electrode 12). Upon the application of a direct voltage across the series combination of the resistance and the capacitance there is a surge of current which lasts until the capacitance has become charged and then subsides. By applying an alternating voltage across this series combination the condenser continually charges and discharges so that there is a continual flow of alternating current through the resistance. This current is increased by increasing the frequency of the source. In this same manner when an alternating voltage is applied between the electrodes 11 and 12 of Figure 1, there is a continual flow of alternating current from the electrode 11 with the resulting continuous production of ions. By applying in addition to the alternating component of voltage between the electrodes of the ionizing structure a direct component of voltage, the ions of charge opposite to that of the electrodes 12 are pulled outward from the region near the wire in which they are formed toward the larger electrodes 12 and thus permeate the entire space between electrodes 11 and 12 through which the gas to be cleaned is directed. I have found extreme-

ly good ionization to be obtained with a frequency of the alternating voltage component of excitation of the order of 200 kilocycles per second though frequencies as low as commercial power line frequencies can be used.

In a second embodiment of my invention as shown in Figure 3, a dielectric member or rod 16 has a conducting film such as aluminum or copper or other conductive material sprayed, plated, sputtered, evaporated or otherwise fastened to its as illustrated by reference character 17 in the diagram. This conducting film may serve as an ionizing electrode and is of such shape that various portions of it form a series of point such that when an alternating potential of sufficient amplitude is applied between the conduction film 17 and cooperating electrodes placed nearby an electrical discharge takes place from the points formed by the conducting film into the gas surrounding the points causing ionization of the gas.

The addition of a second member of dielectric material 18 placed near and arranged substantially parallel to the conducting film 17 as illustrated in Figure 4 increases the electric field gradient in the vicinities of the points formed by the films 17 thus allowing the ionizing electrode 17 to operate at a lower value of alternating current potential. A small space must be maintained between the film 17 and the dielectric member 18 in order that a discharge into the gas surrounding the electrode may take place and in order that the ions formed near the points may have a path through the gas through which to flow outward into the stream of gas to be cleaned.

Figure 5 illustrates another embodiment of my invention in which member 19 is a dielectric rod substantially rectangular in shape which forms the main supporting member of the ionizing electrode 20. Electrode 20 may take the form of a thin metallic stamping, so stamped or otherwise formed so that it has a plurality of pointed sections curved upward and away from the dielectric members 19. Members 19 and 20 are fastened together by means of small rivets 21 only one of which is shown in the diagram. The pointed sections of member 20 are curved away from the dielectric member so that there exists an air space between the points and the dielectric member through which an electrical discharge can take place. When properly excited a bluish glow can be seen to fan outward and downward from the various points toward portions of the dielectric member 19 in the immediate vicinities of the points.

Figure 6 illustrates a typical electrical circuit which may be used to excite all of the ionizing structures described above. In it reference numeral 25 represents a source of alternating current electrical energy such as the secondary winding of a high voltage transformer. Connected in series with each other and with the resulting series combination connected across source 25 are respectively an electrical capacitor 26 and a rectifying device such as an electron discharge device 24. As the cathode 28 of the electron discharge device is connected to one terminal of the alternating current source and as the anode 27 is connected to one terminal of the capacitor 26 the capacitor will be charged to a voltage equal substantially to the peak value of the voltage appearing between the terminals of source 25. The two terminals of the ionizing structure to be excited, namely the ionizing electrode 29 supported by its dielectric rod means 22 and the cooperating electrodes 23, are connected

to the cathode and anode respectively of the rectifying device 24. In this manner the potential difference applied between electrodes 23 and 29 consists of the sum of two components which are the direct current component of voltage existing across capacitor 26 and the alternating component of voltage existing across source 25.

In the following claim it is to be understood that radius of curvature may at times be so small that sharp corners or edges are meant and may at times be infinite such that plane surfaces are meant.

While three embodiments of my invention have been described for the purpose of illustration, it should be understood that the invention is not limited to the exact circuits and arrangements of apparatus herein described, or specifically covered by my claims, as modifications thereof may be suggested by those skilled in the art without departure from the essence of the invention.

What is claimed is:

1. An electrical ionizing apparatus including in combination, a gas medium, a cylindrical conducting electrode having relatively small radius, a solid dielectric cylinder having a radius larger than that of said cylindrical electrode and being made of a material having a dielectric constant substantially greater than that of said gas medium, said dielectric cylinder being parallel to said cylindrical electrode and being in contact therewith through substantially the entire length thereof, at least one cooperating conducting electrode spaced from said first conducting electrode and said dielectric cylinder and having a radius of curvature substantially greater than that of said dielectric cylinder, said dielectric cylinder being positioned with respect to said conducting electrodes to provide a free path through said gas medium between said electrodes unobstructed by said dielectric cylinder so that the electrical capacity between said electrodes is not substantially more than that provided by said gas medium, and a high voltage energizing source coupled across said conducting electrodes for applying a voltage thereto having a direct current component and an alternating current component.

2. An electrical ionizing apparatus including in combination, a gas medium, first and second elongated conducting electrodes extending parallel to each other in said medium, a high voltage energizing source coupled across said electrodes for applying a voltage thereto having a direct current component and an alternating current component, said first electrode having surface regions of small radius of curvature, a dielectric rod made of a material having a dielectric constant substantially greater than that of said gas medium extending parallel to and substantially in contact with said first electrode so that a short discharge path is provided from said first electrode to said dielectric rod, said dielectric rod being positioned with respect to said conducting electrodes to provide a free path through said gas medium between said electrodes unobstructed by said dielectric rod so that the capacity between said electrodes is not substantially more than that provided by said gas medium.

3. An electric ionizing apparatus in accordance with claim 2 in which said alternating current component of said high voltage energizing source has a frequency greater than ten thousand cycles per second, with said alternating

current component having an amplitude of a value at least 5 per cent. of the root-mean square value of the total voltage of said source.

4. An electrical ionizing apparatus in accordance with claim 2 in which said first electrode is in the form of a conducting film on said rod and in which said film includes pointed projections.

5. An electrical ionizing apparatus in accordance with claim 2 in which said first electrode is a metal sheet secured to said rod and including points curved away from said rod.
